SLEEPING CAR.

No. 284,733.

Patented Sept. 11, 1883.

UNITED STATES PATENT OFFICE.

HENRI GUILLAUME, OF WASHINGTON, DISTRICT OF COLUMBIA.

SLEEPING-CAR.

SPECIFICATION forming part of Letters Patent No. 284,733, dated September 11, 1883.

Application filed July 2, 1883. (No model.)

To all whom it may concern:

Be it known that I, HENRI GUILLAUME, a citizen of the United States, residing at Washington, in the District of Columbia, have invented certain new and useful Improvements in Sleeping-Cars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of this invention is to provide suitable accommodations on railway-cars for families or parties traveling together, or individuals who may desire to enjoy absolute privacy; and to these ends the invention consists in the construction of the car-body, and in the arrangement and construction of the sleeping-berths, substantially as more fully described hereinafter, and shown in the accompanying drawings, in which—

Figure 1 is a perspective view, partly in section, of so much of a car-body as is necessary to illustrate my invention. Fig. 2 is a horizontal longitudinal section thereof. Figs. 3, 4, 7, and 8 are detail views, showing the arrangement of the bed-supports. Figs. 5 and 6 are cross-sectional elevations, looking in the direction of arrow of Fig. 2, and showing the closet-door closed and open, respectively; and Fig. 9, a horizontal longitudinal section of a modified construction of car-body.

Like letters of reference indicate like parts wherever such may occur.

The body of the car may be of any suitable form, though in practice I prefer to make the said body A of the car of a series of substantially octagonal compartments, 1, 2, 3, 4, &c., absolutely isolated from one another—that is to say, there is no direct intercommunication between the several compartments by communicating doors. At the intersection of each octagon I locate the lavatory and closet a, &c., so that each compartment will be provided with such lavatory and closet, access to which can only be had by a door, b, from the particular compartment of which such lavatory and closet form an accessory, as plainly

shown in Fig. 2. Access may be had to each compartment, either directly from the ground by a stairway and landing, B, Fig. 9, or by a stairway and corridor, B', same figure, or both, according to the arrangement of the compartments, and, as will be seen in said figure, the entire space of the car-platform is utilized, access being had to the several compartments from the ground by a separate stair and landing arranged on opposite sides of the car. As above stated, and as shown in Figs. 1 and 2, I prefer to construct the compartments in the form of octagons, or substantially in that form, and in such manner as to leave a veranda, C, extending the entire length of the car, on opposite sides of the compartments, and communicating with the front and rear platforms, D, respectively, the entrance to the several compartments being located alternately on opposite sides of the car—that is to say, the entrance E to compartment 1 will be on one side of the car, that to compartment 2 on the opposite side, that to compartment 3 on the same side as the entrance to compartment 1, and so on for all the compartments. By means of this arrangement and construction of car-body I provide not only absolutely isolated compartments, but also a means for gaining access thereto and for promenade; and I also provide a means whereby a person or family may enjoy the privacy of a hotel and regulate the ventilation and heat to suit themselves without incommoding others. Along one side of each compartment I arrange narrow boxes F, F', Figs. 2, 3, 4, 5, and 6, for the reception of the upper and lower bed-supports, G, said supports consisting simply of two side bars, g', and a wire or other netting, g''. The ends of the side bars g' are preferably hook-shaped, as shown at g', Fig. 8, the hook portion thereof sliding in a groove formed in rails h, secured to the transverse partitions of the compartment.

I is a catch, and i a stop that holds the catch in the position shown in Fig. 7, so that when the bed-support is lifted out of its box by side bar g' and the latter run along the grooved rail h the catch i will hold the side bar g firmly in position, while the side bar g', after being fully drawn out, is secured by

means of a pivoted hook or latch, *i'*, Figs. 3, 4, and 6. The box *F*, in which the upper bed-support is placed, has end rails or guides, *f*, along which the support is lifted until the side 5 bar *g* lies against the catch.

K is a linen closet or locker for each compartment, and *L* is a closet in which the mattresses are stored, and both these closets or lockers are closed by a common door, *k*, Figs. 10 5 and 6, said door being partially cut out to fit over the boxes *F* *F*, which are or may be covered by any suitable lid; or they may form a seat or couch, as desired.

Instead of arranging the beds as described, 15 they may be arranged along the transverse partitions and made in the form of drawers *M*, Fig. 2, which, when pulled out, will constitute the berth, and, if desired, both arrangements of beds may be employed, the berths *M* at the 20 foot end projecting under the bed-supports on the side of the car.

It will be obvious that means other than those shown and described may be employed whereby the bed-supports are held in a 25 stretched position, and also that instead of giving the compartments an approximately octagonal form in their general outline they may be of other form in outline, the invention having for its primary object the isolation of 30 the compartments; hence absolute privacy to the individual or family occupying a section, providing all accommodations necessary to comfortable sleeping-apartments, constructing the berths or beds so as to convert the sleeping-apartment into a parlor or saloon section, and, finally, providing a promenade all around 35 the car for the occupants of the several sections.

Having thus fully described my invention, 40 what I claim, and desire to secure by Letters Patent, is—

1. In a compartment-car, a series of compartments each provided with lavatory and closet, and having their entrances and exits 45 alternately from opposite sides of the car by a stairway and landing or a veranda, substantially as described.

2. In a compartment-car, a series of compartments each provided with lavatory and closet, lockers for the bed-supports and bedding, and having their entrances and exits alternately from opposite sides of the car by a 50 stairway and landing or a veranda, substantially as described.

3. In a compartment-car, a series of substantially octagonal sections each having a lavatory, a closet, and an entrance at the intersection of the several octagons, which form landings at that point, as described, for the 55 purposes specified.

4. In a compartment-car, a series of substantially octagonal sections each having a lavatory, a closet, a locker for the bedding and berths, and an entrance at the intersection of the several octagons, whereby landings are 60 formed for said entrances at that point, substantially as and for the purposes set forth.

5. In a compartment-car, a series of substantially irregular octagonal sections having their entrances formed by one of the smaller 70 faces of the octagon at the intersection of two of the sections, whereby landings are formed for said entrances, as set forth.

6. In a railway-car, a car-platform combined with a car-body of less longitudinal and transverse diameters than said platform, whereby a 75 passage or veranda is formed all around the car-body, as and for the purposes set forth.

7. A railway-car composed of a series of sections or compartments having their entrances 80 and exits upon opposite sides of the car alternately, in combination with a veranda or balcony surrounding the entire body of the car, as described.

8. The combination, with the bed-supports 85 *G*, of the rails *h*, having latches *I* *i'*, substantially as and for the purposes set forth.

In testimony whereof I affix my signature in presence of two witnesses.

HENRI GUILLAUME.
